(57) **CLAIM**

We claim the ornamental design for a luminaire, as shown and described.

DESCRIPTION

FIG. 1 is an upper perspective view of a first embodiment of a luminaire showing the new design.

FIG. 2 is a first elevation view of the luminaire shown in FIG. 1.

FIG. 3 is a second elevation view of the luminaire shown in FIG. 1.

FIG. 4 is a top plan view of the luminaire shown in FIG. 1.

FIG. 5 is a bottom plan view of the luminaire shown in FIG. 1.

FIG. 6 is a lower perspective view of the luminaire shown in FIG. 1.

FIG. 7 is an upper perspective view of a second embodiment of a luminaire showing the new design.

FIG. 8 is a first elevation view of the luminaire shown in FIG. 7.

FIG. 9 is a second elevation view of the luminaire shown in FIG. 7.

FIG. 10 is a top plan view of the luminaire shown in FIG. 7.

FIG. 11 is a bottom plan view of the luminaire shown in FIG. 7; and,

FIG. 12 is a lower perspective view of the luminaire shown in FIG. 7.

The elements shown in broken lines are included for the purpose of illustrating portions of the luminaire that form no part of the claimed design.

1 Claim, 12 Drawing Sheets
